UNITED STATES PATENT OFFICE.

CHARLES F. TAVENER AND DANIEL L. PINE, OF CLEVELAND, OHIO.

BOX CUTTING AND PRINTING MACHINE.

SPECIFICATION forming part of Letters Patent No. 531,661, dated January 1, 1895.

Application filed July 10, 1893. Serial No. 480,029. (No model.)

To all whom it may concern:

Be it known that we, CHARLES F. TAVENER and DANIEL L. PINE, citizens of the United States, residing at Cleveland, in the county of Cuyahoga and State of Ohio, have invented certain new and useful Improvements in Box Cutting and Printing Machines; and we do hereby declare that the following is a full, clear, and exact description of the invention, which will enable others skilled in the art to which it appertains to make and use the same.

Our invention relates to box cutting and printing machines, and the object of the invention is to produce an improved machine for simultaneously cutting and printing blanks for paper boxes, substantially as shown and described and particularly pointed out in the claims.

In the accompanying drawings, Figure 1 is a side elevation of a machine embodying the features of our invention, and Fig. 2 is a longitudinal central sectional elevation thereof. Fig. 3 is a plan view of a section of the machine and with the paper roll removed and some of the parts in section to disclose the construction which would appear on a line corresponding to line 3, 3, Fig. 2. Fig. 4 is a side elevation of a section or part of the machine, partially revealed in Fig. 1, and designed here to illustrate more especially the mechanism whereby the feed of the paper may be automatically suspended. Fig. 5 is an enlarged plan view of a section of the endless apron which carries the cutting and printing devices, and showing two sections of said apron with the said mechanism thereon at the center, and designed to illustrate especially the relations of said parts on said sections, as hereinafter more fully described. Fig. 6 is a longitudinal sectional elevation on line 6, 6, Fig. 5, and Fig. 7 is a cross section on line 7, 7, Fig. 5. Fig. 8 is a perspective view of two of the cutter plates separated and shown in detail. Fig. 9 is a diagrammatic view of the box blank showing the outlines thereof as produced by the cutters and in dotted lines as it is creased for folding. Fig. 10 is a plan view of one of the sections or carriers of the endless apron, and Fig. 11 is a similar view with the metal blocks which support the knives attached thereto. Fig. 12 is a side elevation of one of the creasing disks and its eccentric, and a cross section of the shaft —35— on which it is supported, the view corresponding to the view of said parts shown in Fig. 2, 55 and Fig. 13 is a cross section of said parts on a line corresponding to a, a, Fig. 12.

Among the important results obtained by our construction of machine, are economy of material in cutting the blanks, and adaptability of the same form for cutting and printing upon material of different thicknesses without a rearrangement of the parts. The first of these results is effected by providing an automatic cut-off and starter for the paper feed and a peculiar arrangement of the cutters; the second, by having a compressible or yielding support for the printing form.

In the drawings, A represents the main frame or bed of the machine, and B is a rocking frame pivoted on the main frame and adjustable back and forth in respect to said frame by means of the adjusting rods C, or their equivalent, so as to give a fine adjustment to the parts supported upon said frame. 70 As here shown the screw rods C each engage in a nut fixed in or to the frame post B, and the heads of these rods have bevel gears, Fig. 3, which mesh with bevel gears on a cross rod which is constructed at its end to be engaged 75 by a wrench or key to turn it and thereby turn the screws C. A stirrup on the end of the cross rod supports the screws C. In this manner both said screws are turned at the same time and uniformly, and the adjustment 80 of the frame posts B is effected. Other equivalent means might be employed for this purpose.

Power is applied to the machine through the shaft D which has a gear wheel 2 meshing with a large gear 3 on a shaft E, which is the pivot point of the frame B. This large gear 3 meshes with a smaller gear 4 on a shaft F, and upon this shaft F is a steel impression cylinder 5 of sufficient length to cover the 95 width of the paper which passes beneath the same in the operations of the machine from the roll 6 on the shaft G and over the small roll 7 on the shaft H. The paper roll 6 is turned by the roll 7, and the roll 7 is turned 100 by the cylinder 5, which in turning is operated from the shaft D by the gear mechanism hereinbefore described. Now, the cylinder 5 being supported in suitable bearings upon the

frame B (see dotted lines Fig. 1), it follows that the position of said cylinder with reference to the paper and the mechanism beneath the same over which the cylinder passes is 5 adjustable as to its elevation and the measure of its pressure downward by means of the screw rods C arranged and constructed to adjust the frame B as hereinbefore described.

Having this construction for supplying the 10 paper and making the impression, we provide an endless apron consisting of a series of cross pieces or carriers 8 connected at their ends by means of brackets 9 with the sprocket links 10. For convenience of connection the 15 bracket 9 has inside ledges 11 upon which the links 10 rest, and over the link is a fastening device 12 pressed down thereon by set screws 13, thereby fastening the link securely to said bracket but leaving all the parts in condition 20 for adjustment and detachment, if desired, without affecting in any manner the link connections one with another. In a like manner the wooden cross piece or carrier 8 is held upon the bracket by means of the set screw 25 14 bearing, in this instance, upon a plate 15 which in turn bears upon the cross piece 8. A similar construction obtains at both ends 30 of said cross piece or section 8 and the same construction and connection of parts prevails 35 throughout the endless apron. To support said apron midway along its top, we provide a suitable shelf or table 16 over which the apron slides as it travels toward the point where the cutting and printing occur, and 40 the brackets 9 have a corresponding bar 17 at each side over which they slide and which serve to take the weight of the ends of the sections and of the chain and brackets. Each 45 of said sections or carriers 8 is designed to receive castings or metal blocks 19 and 20, shown in Fig. 11, and set in the notches or recesses formed in said section. These blocks are meant to have the shape of the paper box blank to be formed and their configuration 50 will of course be changed as the style of the box is changed, and the knives and creasers are designed to be attached to these blocks 19 and 20. Thus, we have in Fig. 8 the two cutters 21 and 22 adapted to be secured upon 55 the blocks 19 and 20, as shown, for example, in Figs. 5 and 7, Fig. 7 showing said parts in section so as to more clearly reveal their relation to one another. Any sufficient means 60 may be adopted to secure the said cutters to the blocks, and we make no claim therefor. As here shown we use separate foot pieces bent to be screwed down to the blocks at one end, as plainly seen in Fig. 8, and having the other end engaging the cutters through slots 65 cut for this purpose, and having the outer end of said foot pieces bent down against the back of the cutters. This, however, is only

one of a number of ways which any skilled mechanic could suggest.

Besides the knives or cutters 21 and 22 70 which come along one edge of the box blank, there are corresponding cutters which come along the opposite edge, and then there are creasers 23 to crease the blank as seen by dotted lines 24, Fig. 9. These are dull blades 75 instead of sharp ones and when the paper is pressed down upon them they form creases in the paper instead of cutting it, and these creases serve as lines upon which the box is folded. 80

Intermediate of the cutters as described are blocks 25 on which we secure stereotype plates 26 for doing the printing, and these blocks are fixed upon the strips, plates or bars 27 extending centrally and longitudinally 85 over the sections 8 and held thereon by means of the small bolts or screws 28, shown in Fig. 6. At each end beneath the said blocks 25 and the plates 27 are a pair of springs 30, Fig. 7, which serve to hold the block and its 90 stereotype plate normally above the level of the cutters, so that in passing beneath the inking rolls 31 the cutters will not injure the said rolls. In the sections thus equipped with printing plates and cutters, the said plates 95 would stand above the cutters as they reach the cylinder —5—, Fig. 7, if they were not depressed; but they must be depressed against the springs —30— to a level with the cutters, and this is effected by cross strips or bars 100 —32— fixed at their center to the ends of plates or strips —27—, Figs. 5 and 6. These strips —32— are long enough to extend beyond the printing blocks —25—, so that the impression cylinder —5— will strike them 105 before it does the printing plate or type and depress the same to avoid abrupt contact with the said cylinder. The said pieces or strips —32— are therefore of such elevation as to do this work and come up nearly or 110 quite as high as the top of the plates —26—.

The paper roll 6 has its shaft G so supported that the shaft is adapted to fall as the paper is drawn off and thus keep constantly in contact with the roll 7, and the said roll 7 115 is supported by means of links 34 pivoted on a shaft 35, which in turn is journaled in brackets 35' on the frame B, the brackets being provided with set-screws 35" for holding the shaft rigidly in its bearings. Secured to the shaft are a series of creasing disks 36 each arranged upon an eccentric 37 adjustable longitudinally on the shaft so that the distance between the creasing disks may be varied to form the creases 27' (Fig. 9) for different sizes 120 and styles of boxes.

It will be seen in Figs. 12 and 13 that the eccentric is sleeved and splined on the axle —35— so as to be rotated therewith, and has a set screw —45— to fix it upon said shaft 130 when moved longitudinally thereon to any given position. The creasing disk —36— is fixed upon this eccentric by means of a ring or collar —46— secured at the side of the ec-

centric by suitable screws, and in such manner as to leave the disk or creaser free to rotate on the eccentric. When the creasers are to be adjusted toward or from each other to operate in different relations, the eccentric head with its attached creaser is moved bodily upon the shaft —35— and then fastened thereon by the set screw —45—; and when it is desired to vary the distance between the creasers and roll 7 to make a more or less decided crease shaft 35 is rotated so as to move the eccentric nearer to or farther away from the roll and the shaft then secured from further rotation by set-screws 35''. There is little waste in the paper because the blades which cut the paper into blanks form a complete blank from it, and the cutters come within an eighth of an inch of each other. Nearly the exact width of paper to form the blank is used so that there is little waste on the sides, but to insure uniformity we employ trimming disks 38 on the shaft 35 outside the creasers 36.

In case one or more of the carriers or sections 8 should be omitted from the endless apron so that there would be a vacancy, and an unavoidable waste of paper corresponding to the vacancy if the paper continued to roll all the time, we have provided an automatic stop for the paper roll so that it will stop rolling until more paper is required, and this is the purpose of the mechanism shown distinctly in Fig. 4, which is calculated to raise the roll 7 from the cylinder 5 temporarily and while the vacancy occurs, and to throw said parts into contact again when the vacancy has been passed. To this end we replace the brackets —9— for the section that may be omitted and on the next section following with similar brackets —9'— having lugs —9²— on their top. In the drawings we show a number of sections omitted. Brackets 9' are arranged to engage a laterally projecting pin —10²— on a swinging bar —10²— pivoted at its ends to suitable links —10³— supported from the main frame. This bar —10²— has other pins on its opposite side between which extends a lever —10³—, and this lever is free to rotate on a shaft —10⁴— which extends entirely across the machine so as to raise the roller —7— uniformly at both ends. Upon this shaft —10⁴— are hexagons —10⁵—, one on each end of said shaft and rigid therewith. The hexagons rest upon brackets J secured to frame B. Shaft 10⁴ is suspended in hangers —10⁶— which go to the shaft H of roller —7—. A ratchet wheel —11²— is fixed on the shaft —10⁴—, and a catch or dog —11³— is on the head of the lever —10³— and arranged to engage the said ratchet wheel. Now, in operation the endless apron will move along and when the bracket —9'— with its lug —9²— comes to the pin —10²— it will move the bar —10²— forward and thus cause the lever —10³— to rotate to the position seen in Fig. 4. This in turn through the action of the dog and ratchet causes the hexagon to move

from its lower flat position —a— to the next higher position —a'—. In taking this position the effect is to raise the roller —7— from the cylinder —5—, as seen in Fig. 4, and thus stopping the feed of the paper. Now, as shown in the drawings, as all the brackets are omitted behind the bracket —9'— at the top in Fig. 4 to the bracket —9'— at the bottom of the endless apron Fig. 4, it will be seen that the next bracket which comes into action will be —9'— at the bottom on the next section following, and its operation upon the lever —10³— through the intervening mechanism will be repeated and this will restore the hexagon to its next lower position on the rod and drop the roller —7— again upon the cylinder —5—. The effect of the lever —10³— upon the shaft and hexagon is to rotate said parts through the intervention of the dog from one position to the other when the lever is moved by the bar —10²—. Then when the lug —9²— passes pin —10²— the bar —10²— is drawn back by the spring —12'—, and this carries the lever back with it and of course causes the dog to slide over the teeth to engage a lower tooth on the left. In this movement, however, the hexagon and the shaft remain stationary. Then as the next bracket —9'— comes along the hexagon and shaft with the ratchet thereon are carried to the next position in rotation, and so on.

The endless apron is connected by sprocket chains along its sides and turns on rollers 40 and 41 provided with sprocket wheels on which the links 10 of said chains engage.

If the boxes are not to be printed the stereotype plates or their equivalent, as forms set in type or type bars, are omitted.

The cutters 21 and 22 have notches by which one cutter is adapted to set over and upon the other, and which serve to interlock the said cutters and to assist in holding them in proper position and relations for work.

It will be noticed that there is an idler in the shape of a cylinder, 47, which comes within the endless apron and immediately beneath the impression cylinder 5, and is adapted to take the pressure from said impression cylinder, there being just the proper amount of room between the said cylinder and the idler for the endless apron to pass through and to have the printing occur on the paper, and the paper cut into blanks or box lengths as herein described.

The carriers or sections 8 of the endless apron may be with their edges formed as they now appear with the blocks 19 and 20 attached thereto and serve the same purpose, but for convenience we make the section of wood with recesses in its edges, as shown, and attach special metal blocks to complete the structure.

The product of the machine is a blank for making a paper box having the size, shape, and outlines desired and cut and printed and increased ready for folding or making up. Different sizes and shapes of boxes may be made

by changing the machine in the particulars necessary to produce the other form or forms desired.

5 Any suitable inking arrangement may be adopted.

The waste from the cutters is very slight and is gotten rid of as the endless apron turns over its rolls and separates the knives of the sections 8, the waste then dropping to the floor.

10 Two or more sets of cutters and printers may be arranged on each carrier 8, and wood veneer or other flexible material may be used instead of such paper as boxes generally are made of.

15 Having thus described our invention, what we claim as new, and desire to secure by Letters Patent, is—

1. The herein-described machine for cutting and printing blanks, consisting of a series 20 of transverse bars and chains connecting said bars at their ends and forming together an endless apron, a depressible printing form secured to each of said bars and knives to cut the blank fixed to said bars at the outside of 25 and between the opposite edges of said printing forms, and the platen or cylinder whereby the impressions are made and the blanks are cut, substantially as set forth.

2. The herein-described machine comprising 30 a carrier having knives to cut the blank, a printing form depressibly secured to said carrier so as to have a yielding contact with the impression platen or cylinder and projecting beyond the cutters, the platen or cylinder, 35 the said parts adapted to cut and print the blank at a single impression, and means for depressing the printing form before it reaches the platen, substantially as set forth.

3. In the herein-described machine, the 40 combination of a carrier having knives to cut the blank, a printing form yieldingly secured to said carrier and projecting beyond the cutters, an impression platen or cylinder, and means for depressing the printing form before it reaches the said platen or cylinder comprising 45 bars 32 connected with the printing form arranged to be engaged by the platen or cylinder, substantially as shown and described.

50 4. The herein-described machine comprising devices for feeding the material to be cut, an impression platen or cylinder, a series of removable carriers having knives to cut the blank, and means for stopping the feed of 55 the said material when a carrier blank-space

passes before the platen and for automatically starting the same on arrival of the next carrier, substantially as set forth.

5. In the herein-described machine, the combination of the feeding roll 7 journaled 60 in a movable bearing, impression platen or cylinder 5, a series of removable carriers having knives to cut the blanks, lug 9² connected with the series of carriers, swinging bar 10² to be engaged by lug 9², retracting spring 12', 65 lever 10³ loose on shaft 10⁴ and connected with bar 10³, the said shaft, a pawl and ratchet connection between lever 10³ and the shaft, the polygonal plate 10⁵ rigid on said shaft, a support for plate 10⁵, and link 10⁶ connecting 70 the aforesaid shaft and the shaft of roll 7, all constructed and operating substantially as set forth.

6. The endless apron having flat cross pieces or carriers and separate metallic blocks secured to said pieces between their ends and having edges corresponding to the edges of the box to be cut, and cutters fixed to said edges, substantially as set forth.

7. The endless apron having the carriers or 80 cross pieces with cutters on their edges and a printing form on a spring supported base, in combination with an impression cylinder and means to depress said printing form even with the cutters when it approaches the impression cylinder, substantially as set forth.

8. The main frame, the pivoted frame thereon adjustable back and forth in respect to the main frame, the paper roll, the impression cylinder and the roller between said roll and cylinder supported on said pivoted frame and arranged to turn one upon the other, in combination with an endless apron having carriers with cutters and a printing form between the cutters, substantially as set forth.

9. The creasing device comprising shaft 35 rotatable in its bearing, means for holding said shaft from rotation, eccentric 37 secured to the shaft and adjustable longitudinally thereon, means for holding the eccentric in position, and the creasing disk rotatable on the eccentric, substantially as shown and described.

Witness our hands to the foregoing specification this 24th day of June, 1893.
